UNITED STATES PATENT OFFICE.

HENRY A. HEINE, OF WASHINGTON, DISTRICT OF COLUMBIA.

CLOSURE FOR BOTTLES, JARS, AND THE LIKE.

1,145,243.

Specification of Letters Patent.

Patented July 6, 1915.

Application filed September 23, 1914. Serial No. 863,095.

To all whom it may concern:

Be it known that I, HENRY A. HEINE, a citizen of the United States, residing at Washington, District of Columbia, have invented certain new and useful Improvements in Closures for Bottles, Jars, and the like, of which the following is a specification.

This invention relates to closures or stoppers for bottles, jars and the like, and more particularly to closures of the disk type, such as is commonly used in milk bottles.

The object of the invention is to provide a closure or stopper having openings with closures for the same, and means common to said closures for displacing the same to open said openings.

A further object of the invention is to provide means for displacing closures for the openings which also maintains said closures in open position.

Another object is to provide a closure of the flat disk type having a grip, pull handle or finger piece for removing the same that will not interfere with the operation of the ordinary or usual type of bottle capping machine.

Another object of the invention is to provide a closure of the type which is seated in the neck of a bottle or the like and grips the side walls thereof having a portion adapted to be removed or displaced to provide a pouring opening without impairing the grip between said closure and the bottle.

Other objects of the invention will appear from the description in the specification and illustration in the drawings.

The invention consists in certain features of construction and arrangement described in the following specification and claims, and clearly illustrated in the accompanying drawings, in which,

Figure 1 is a top plan view of one form of my improved closure. Fig. 2 is a section on line 2—2 of Fig. 1. Fig. 3 is a plan view of a modified form. Fig. 4 is a section on line 4—4 of Fig. 3. Fig. 5 is a plan view of another modified form. Fig. 6 is a section on line 6—6 of Fig. 5. Fig. 7 is a plan view of a further modification. Fig. 8 is a section on line 8—8 of Fig. 7. Fig. 9 is a plan view of another form of the invention. Fig. 10 is a plan view of still another modification. Fig. 11 is a section on line 11—11 of Fig. 10.

Referring to the drawing, it will be noted

that the invention is illustrated in several embodiments. In all of the forms, there is provided an outlet and vent opening each closed by a flap, and means common to the flaps for opening the same.

In the form shown in Figs. 1 and 2, the numeral 1 designates the body of the cap, which is preferably a flat disk of paper, paste-board or the like material, usually coated with paraffin, beeswax or the like. Arcuate slots 4 are provided in the cap, partially severing portions thereof, thus forming flaps 2 and 3. A thin pliable wire 5 lies flat upon the face of the cap with its ends firmly secured one to each of the flaps 2 and 3. The wire 5 is a staple and is secured to the cap by an ordinary wire stapling machine. The wire is pressed down into the material of the cap so that the top thereof is substantially flush with the top surface of the cap. This enables the cap to be used in connection with any ordinary capping machine. The flaps 2 and 3 are adapted to be displaced from the plane of the body of the cap, as shown in Fig. 2. The wire 5 serves as a grip or finger piece to displace the flaps. When the flaps are pulled out, the outlet and vent openings are exposed, allowing the contents of the container to be removed. In pulling out the flaps by means of the wire 5, the same is bent, as shown in Fig. 2. In its bent condition, the wire, as will be readily seen, serves to hold the flaps away from the openings. Furthermore, when the flaps are in closed position, the wire 5 holds them closed. The wire is pliable but not elastic, so that when bent it remains so and has no tendency to resume its former position.

In Figs. 3 and 4, a peculiar manner of fastening the wire to the flaps is shown. The wire first passes over the flaps and bridges the slots 4. The ends of the wire pass through the body of the cap to the underside thereof close to the edges of the slots 4. They are then bent at substantially right angles, passed back over the slots 4 on the underside of the cap, and turned upwardly and forced into the material of the flaps. The wire bridging the slots 4 and passing through the body of the cap more effectually prevents unintended displacement of the flaps. In order to displace or pull out the flaps, the wire 5 must first rupture the material of the cap between the wire and the edge of the slot 4.

In Fig. 7, the flaps are each formed by two slots 6-7 and 8-9, having uncut portions 10-11 respectively between their adjacent ends. The ends of the wire 5 are secured to the flaps, and in order to displace said flaps, it is necessary to rupture the uncut portions of the cap 10 and 11. The object of providing the uncut portions 10 and 11 is to more securely retain the flaps in position against accidental displacement.

In Fig. 6, a form similar to that illustrated in Fig. 7 is shown. In this form, however, the ends of the wire 5 are secured to the uncut portions 10 and 11 of the body 15 of the cap. This construction aids in rupturing the portions 10 and 11. The ends of the wire, after passing through the uncut portions 10 and 11, are bent backward along the underside of the cap and secured to the flaps, as shown in Figs. 2, 4 and 8.

Fig. 9 shows a modification in which one of the flaps is formed by scoring the material of the cap along the line of a chord, as at 12, while in Fig. 10, both of the flaps 25 are formed by scoring the material of the cap on lines 13 and 14. In all of the forms the flaps may be formed by score lines instead of slots cut through the material of the cap. While the slots which form the 30 flaps are shown as arcuate slots, they may have various other configurations, it being merely essential that they provide or define partially severed portions forming flaps adapted to be displaced to expose openings 35 in the cap.

It will be noted that in Figs. 1 to 8 the openings in the closure are entirely within the periphery thereof and that the periphery is unbroken throughout its entire extent. This is an important feature for the 40 reason that the grip between the closure and the bottle or jar is not impaired at any point. Generally when it is desired to remove the contents or a part of the contents 45 of a container provided with the closure hereinbefore described, the closure is not removed but the flaps are merely displaced and the contents removed through the openings thus exposed. Some pull is exerted on 50 the closure in displacing the flaps and it is essential that the grip between the closure and the bottle be maintained at its maxi-

mum in order that the closure may not be pulled out of its seat.

It will be understood that changes in the 55 form, proportion, size and minor details may be made within the scope of the claims, without departing from the spirit or sacrificing any of the advantages of the invention.

60

I claim:

1. A closure of the character described having portions thereof partially severed, and a wire bridging said severed portions and having its opposite ends extending 65 through the same and bent back thereagainst and secured thereto.

2. A closure of the character described having portions thereof partially severed to form flaps, and a wire having its opposite 70 ends secured respectively to said flaps and positioned with its upper surface flush with the surface of said closure.

3. A closure of the character described provided with flaps formed therein, and a 75 wire lying flat upon the surface of said closure and having its opposite ends secured to said flaps.

4. A closure of the character described provided with partially severed portions 80 forming flaps, a wire disposed flat upon the surface of said closure and passing across said flaps, the opposite ends thereof passing through the closure and bent backwardly and secured to said flaps.

5. A closure of the character described, provided with flaps formed therein, and flexible means for opening said flaps lying flat upon the surface of the closure and connected at its opposite ends to the flaps.

6. A closure of the character described, provided with flaps formed therein, and a strip lying flat upon the surface of the closure and connected to said flaps, said strip having sufficient rigidity to maintain said 95 flaps normally in closed position and being flexible to allow of opening the same.

In testimony whereof I affix my signature in presence of two witnesses.

HENRY A. HEINE.
